DESIGN FOR A JEWELRY PIN OR SIMILAR ARTICLE

Frank Morrow, Johnston, R. I.

Application October 26, 1945, Serial No. 123,207

Term of patent 3½ years

(Cl. D45—19)

To all whom it may concern:

Be it known that I, Frank Morrow, a citizen of the United States, residing at Johnston, in the county of Providence and State of Rhode Island, have invented a new, original, and ornamental Design for a Jewelry Pin or Similar Article, of which the following is a specification, reference being had to the accompanying drawing, constituting a part thereof.

Fig. 1 is a front elevational view of the jewelry pin showing my new design; and

Fig. 2 is a side view thereof.

I claim:

The ornamental design for a jewelry pin or similar article, substantially as shown.

FRANK MORROW.
